Inventor:

O. H. Taylor

United States Patent Office.

O. H TAYLOR, OF BROOKLYN, NEW YORK, ASSIGNOR TO WILLIAM E. PARISH, OF NEW YORK CITY.

Letters Patent No. 82,044, dated September 8, 1868.

IMPROVEMENT IN BIT-STOCKS.

The Schedule referred to in these Letters Patent and making part of the same.

TO ALL WHOM IT MAY CONCERN:

Be it known that I, O. H. TAYLOR, of the city of Brooklyn, county of Kings, and State of New York, have invented a new and useful Improvement in Securing Bits and other Tools in Bit-Stocks, (for boring-bits;) and I do hereby declare that the following is a full and exact description thereof, reference being had to the accompanying drawings, and to the letters of reference marked thereon.

The nature of my invention consists in providing a bit-stock with a transversely V-shaped opening to receive the bit, said opening being wider at the side next the thumb-screw than at its opposite side, and being transversely V-shaped with the longitudinal line of the bit when in position; also, providing a substantial boss for the thumb-screw to pass through, to prevent the threads of the screws from stripping.

The object of my invention is to provide a simple and durable adjustable bit-holder or stock.

To enable others skilled in the art to make and use my invention, I will proceed to describe its construction and operation.

Figure 1, in the accompanying drawings, represents a top view of the portion of a bit-stock, that holds the bit.

Figure 2 represents a side elevation of the same, showing a portion of the handle D.

Letters of like nature and kind refer to like parts in both the figures.

I construct my bit-stock in any of the known forms except that portion that receives and holds the bit, shown at A A, which said portion A A has formed through its centre an opening or hole unlike other bit-stocks, it, the said hole, being made narrower at the back, as shown at the termination of the red line P at J, fig. 1, than it is at the side next to the boss B, so that when the bit G (as shown) is inserted into the opening, the thumb-screw C being turned back so that the bit may be kept close to the side next to the boss, it will be observed that the bit having a transversely-square shank, it cannot go into the socket far enough to touch the back at J, the termination of the red line P, (providing the shoulder of the bit is large enough to prevent it from going entirely through the socket,) consequently there will be an open space for the bit to be forced into by the screw. Said space being transversely wedge-form, causes the bit to be held in a very firm manner, when the screw is properly set against it, without fitting, it readily adjusting itself by the pressure of the screw to the V-form of the opening.

I usually make the opening in my bit-stock for the bit, with three sides at right angles, as shown in fig. 1, and the other beveling, so as to converge toward the centre of the opening J at the back, and opposite the boss B, the object being to give the bit a solid bearing against two of its relative diagonal corners when in use.

I also combine a projection or boss, B, with my bit-stock, for the screw C to pass through, of sufficient thickness to give the necessary amount of metal to keep the screw-thread from stripping, as they generally do in ordinary thumb-screw bit-stocks after a little use.

It will be observed that the opening for the bit in my bit-stock is longer (transversely) the way the red lines run than it is across them, and may be carried to any practical extent on the same principle, so that the largest and smallest bit-shank may be firmly held in the same socket without adjustment.

Having thus fully described my invention, what I claim, and desire to secure by Letters Patent, is—

The socket A, contracted at one side, and adapted for the reception of a shank of a tool which may be secured in the stock by a screw, or its equivalent, so applied as to force the shank into the contracted portion of the socket, substantially as described.

O. H. TAYLOR.
